CLAIM

The ornamental design for a lawn mower, as shown and described.

DESCRIPTION

1. Lawn mower

1.1 : Front

1.2 : Back

1.3 : Left

1.4 : Right

1.5 : Top

1.6 : Bottom

1.7 : Perspective

1.8 : Perspective

Reproduction 1.1: front view of design 1; reproduction 1.2: back view thereof; reproduction 1.3: left view thereof; reproduction 1.4: right view thereof; reproduction 1.5: top view thereof; reproduction 1.6: bottom view thereof; repro-

(Continued)

duction 1.7: perspective view (front, top, right side) thereof;
reproduction 1.8: perspective view (back, bottom, left side)
thereof.

1 Claim, 8 Drawing Sheets
